CLEANING DEVICE

Carl E. Lang and Charles Lee Boggs,
San Francisco, Calif.

Application April 13, 1933, Serial No. 666,003

12 Claims. (Cl. 141—1)

The present invention relates to improvements in cleaning devices, and has particular reference to a device for cleaning watches and parts thereof.

In cleaning watches it has been the conventional practice to effect the cleaning by rapidly revolving the watch mechanism in a cleaning fluid, but this method is not very satisfactory since the revolution of the mechanism in a liquid at high speed causes the liquid to be thrown away from the mechanism by centrifugal force so that a pocket is formed about the mechanism which leaves at least a portion thereof exposed to air or gases formed in the cleaning fluid. As a rule liquid ammonia has been used as the cleaning fluid, and the gases created in the pocket about the revolving watch mechanism have the effect of tarnishing or oxidizing the metal so that the result in many cases is entirely unsatisfactory.

One of the important objects of the present invention is to overcome this difficulty, and it is proposed to arrange the mechanism in such a manner that the watch or whatever object is to be cleaned does not revolve in the center of a rotating fluid body, but is made to revolve off center relative to the body. This causes the rotating liquid to continuously return to the pocket or vortex set up by the rotating mechanism and to keep the same filled so that the object to be cleaned is at all times in contact with the liquid instead of being subjected to the action of gases. When the fluid is rotated as stated, a vortex is formed in its center. It has been found that by disposing the axis of the object to be cleaned laterally of the wall of the vortex in the rotating fluid so as to be substantially clear of said vortex there will be a practically complete submergence of the object, thereby achieving the main purpose of the invention.

A further advantage of this eccentric mounting of the object to be cleaned relative to the liquid body is that the object is really subjected to a double washing action, one being caused by the revolving movement of the object itself in the liquid, and the other by the fact that the object instead of being mounted in the center of the liquid body is mounted in a rim section thereof so as to be subjected to the washing action of the revolving body of liquid. We have found that the placing of the rotating object slightly to one side of the center line and still having the rim of the object extend beyond the center line, that the body of fluid will be rotated by the rotating object, and will form a vortex coinciding with the center line. This will cause the fluid to

wash through the object and prevent the formation of a vortex along the axis of the rotating object.

It is further proposed in the present invention to provide for further improvements in connection with a cleaning device of the character described which will allow the entire operation to be carried out with more simplicity and greater economy.

It is proposed to provide convenient mounting means for the fluid receptacle in connection with means for mounting a motor and the cleaning apparatus relative to the fluid receptacle so that the same may be handled as a unit.

It is further proposed to provide certain improvements in holding means for the watch mechanism, whether the same be manipulated in a single piece, or taken apart in its constituent parts.

Further objects and advantages of our invention will appear as the specification proceeds.

The preferred form of our invention is illustrated in the accompanying drawings, in which

Figure 1 shows a side elevation of the entire apparatus;

Figure 2 a top plan view thereof;

Figure 3 a detail view in section of a holding means for a watch mechanism;

Figure 4 a bottom plan view of the holding means with a watch mechanism shown in place;

Figure 5 a bottom plan view of the holding device per se;

Figure 6 a side elevation of the holding device with a perforated cage attached thereto;

Figure 7 a top plan view of the assembly shown in Figure 6;

Figure 8 a bottom plan view of the same assembly; and

Figure 9 a detail view in perspective of a gripping jaw used in our invention.

While we have shown only the preferred form of the invention we wish to have it understood that various changes or modifications may be made within the scope of the claims hereto attached without departing from the spirit of the invention.

Referring to the drawings in detail, Figure 1 shows a base 1 having means associated therewith for holding three different containers 2 thereon, the first container being provided with a cleansing fluid, such as liquid ammonia, and the two other containers being provided with rinsing fluids for a first and second rinsing of the objects to be cleaned. The containers 2 are preferably round in cross section, and each con-

tainer is firmly held to the base 1 by means of four springs 3 rising from the base in spaced relation, the springs bearing against the sides of the containers. The four springs 3 form two pairs, and the two springs of each pair are interconnected at their upper ends by spring members 4, which are curved to encircle the upper end of the container so as to allow a cover 5 to be placed on the upper rim of the container 5. The cover 5 is provided with two projecting tongues 6, which when the cover is lowered upon the container should be disposed between the two pairs of springs so as to clear the members 4, and which may be pushed underneath the members 4 by a turning movement 10 for clamping the cover upon the container. The spring members 4 are curved downwardly in their central section so as to tighten the cover on the turning movement, and the tongues 6 are 15 made curved so as to facilitate the engagement 20 at the beginning of the turning movement.

The cover 5 has the motor 7 permanently secured thereto and the motor shaft extends through the cover, the motor being mounted eccentrically relative to the cover so that the motor shaft extends into the container 2 eccentrically. The motor preferably has a second cover 8 secured to the other end thereof, the second cover 8 being substantially the same as the cover 5, and 25 being coaxial therewith so as to be also eccentric relative to the motor. The cover 8 has lugs 6' and a gasket 8' for forming a liquid-tight seal between the cover and the container 2. The cover 5 may likewise be provided with a gasket 30 (not shown). The other two containers 2 are provided with removable covers 2'.

The three containers 2 are substantially alike and the covers 5 and 8 with the motor 7 may be secured thereto in the same manner.

40 The motor shaft has the holder for the watch mechanism secured thereto, the holder being illustrated in Figures 3, 4 and 5. The holder comprises in its principal features supporting means in the form of a disc 9 through the center 45 of which extends a reduced portion 10 of a shaft 11, which has a pinion 12 secured thereto, the pinion being accommodated in a recess in the disc. The latter has two jaws 13 of which one is shown in detail in Figure 9, disposed thereon in 50 coacting relation, each of the jaws having a rack 14 extending therefrom and the two racks being slidably mounted in grooves 15 of the disc so as to be in engagement with the pinion 12. It will be readily seen that revolving movement of 55 the pinion 12 in one direction or the other will cause the jaws to move.

Revolving movement of the pinion 12 is brought about by means of a sleeve 16 which is threaded upon the shaft 11 as at 17, and the movement 60 of which relative to the shaft is limited by means of a fixed collar 18. The sleeve in actuating the pinion is first rotated on the shaft 11 until it abuts the nut 18. Further rotation of the sleeve 16 in the same direction will now rotate the shaft 65 11 and with it the pinion 12 for opening the jaws 13. Within the sleeve 16 is accommodated a spring 19, the function of which is to oppose separating movement of the jaws and to clamp the jaws upon an interposed object when the 70 sleeve 16 is released by the operator. The jaws are V-shaped as will be seen from Figure 9, and the rack 14 of each jaw is offset and extends from an end portion of the jaw so that the two racks 75 may operate on opposite sides of the center of the disc, while the two jaws are centrally oppo-

site to one another. The shaft 11 has a bore in its top for receiving the motor shaft 20, and the wall of the bore is split longitudinally and its outer surface is provided with a tapered thread. The shaft 11 may be clamped upon the motor shaft indicated at 20 by means of a nut 21 threaded upon the tapered and split end of the shaft 11 which as just stated is cored to receive the shaft 20. The jaws 13 each have inclined sides 13' which extend at an angle with respect 10 to each other for gripping and centering the watch mechanism. The sides are spaced from each other at their inner ends for providing a recess 14' for receiving the stem of the watch mechanism. When the watch stem is received in either of the recesses 14' the fourth pinion (not shown) of the watch mechanism, which carries the second hand, will be disposed midway between the two jaws 13 and will be protected 15 against breakage. It will also be observed that the shape of the jaws will center any type of 20 watch mechanism, whether round, oval, square or rectangular. The watch will rest on the faces of the gripping jaws and the slanting sides 13' 25 will urge the watch down on the faces while the fact that the same sides 13' on each jaw are inclined with respect to each other, will cause the watch to be centered between the jaws.

The jaws 13 are adapted to grip the watch 30 mechanism as a whole but sometimes it is to be preferred to separate the mechanism into its constituent parts, and in that case we preferably use a cage such as illustrated in Figures 6, 7 and 8 for accommodating the parts. The cage 35 22 is a cylindrical housing formed with a large number of small perforations, and preferably formed with a partition 23, also of perforated material which extends from a diametric line 24 at the top 23' of the housing, and at an angle 40 to the bottom 24' of the casing so as to form one small compartment 25 for accommodating the small parts of the mechanism, and a larger compartment 26 accommodating the larger parts 45 of the mechanism. It will be noted that the entrances to each compartment are of equal size. The cover 27' of the cage is hinged thereto as 50 at 28, and may be held in place by a retracting spring 29 adapted to enter a slit 30 in the cage housing. The opposite or bottom end of the 55 cage housing has a cylindrical extension 31 formed with a number of slots indicated at 32, and this end is used for securing the cage to the disc 9. It will be noted, particularly from Figure 5, that when the two jaws 13 are in their most inward position, the operating racks 14 of 60 the jaws extend slightly beyond the periphery of the disc. When the jaws are separated, the operating racks move inwardly and the extremities of these operating racks are used for fastening the cage to the disc. The cylindrical extension 65 31 of the cage fits over the disc when the operating racks 14 are retracted, and after the disc has been placed relative to the cage the extremities of the operating racks 14 are allowed 70 to project thru the slots 32 for holding the cage to the disc. The cage 22 is shown inverted in Figure 6 and this is the position it assumes when rotating in the fluid. When adding or removing articles from the cage, the cage is reversed from 75 the position shown before the cover 27' is removed. The terms top 23' and bottom 24' are given to the cage when in a position to have articles added or removed therefrom, which is opposite from the position shown in Figure 6. 75

The operation of the invention will be readily understood from the foregoing description.

If it is desired to clean the mechanism as a unit it is clamped between the jaws 13. For this purpose the operator first turns the sleeve 16 away from the disc 9 until it strikes the collar 18 whereupon turning movement is continued and the shaft 11 is made to turn with the sleeve whereby the pinion 12 is turned and the jaws 13 are made to separate, the operator holding the disc against rotation. During this outward movement of the jaws the spring 19 is placed under tension and when the jaws have been separated sufficiently far to accommodate the watch mechanism the latter is placed between the jaws and the operator releases the sleeve 16, which causes the spring 19 to urge the jaws upon the watch mechanism. After the latter has been clamped in place the jaws may be positively locked by a return movement of the sleeve 16 upon the disc whereby the pinion 12 is tightened upon the disc, and whereby the jaws are positively locked against rotation in either direction irrespective of the spring 19.

After the watch mechanism has been positioned in this manner and the shaft 11 has been secured to the motor shaft 20 by means of the nut 21, the cover 5 is engaged with the first container 2 in the manner previously described so that the watch mechanism is mounted within the container eccentrically thereof, and is submerged in the cleaning liquid. The mechanism is now rotated at high cleaning speed, and a thorough cleaning of the mechanism is effected, the latter being subjected to the double washing action previously described, and the creation of an air or gas pocket being prevented by the revolving liquid washing back into the pocket on account of the eccentric mounting. The initial rotation of the shaft 20 will cause a vortex to be formed about the watch mechanism. This is immediately filled by fluid because the rotating watch mechanism will cause the body of fluid in the container to rotate about the axis of the container. The vortex will therefore move from the axis of the shaft to the axis of the container. The rotating watch will therefore have its parts bathed in the fluid for each rotation of the shaft. Experiments have shown that a round container 4" in diameter and 7" high filled with fluid to within 2" from the top will form a vortex in the fluid when the object is rotated at a cleaning speed of from 250 R. P. M. and upward. A rotating object placed in this rotating body of fluid with its axis near the wall of the vortex will be thoroughly cleaned, as already set out.

After a sufficient period for cleaning the mechanism has elapsed the entire device, preferably with the motor still running, is lifted out of the first vessel and reintroduced in the second vessel for rinsing operation, and thereafter the entire mechanism is transferred to the third container 2 for a second rinsing operation. The mechanism is then removed from the third container and is now reversed whereupon the second cover 8 is secured to one of the containers in the same manner as the cover 5 was previously secured. Now the shaft with its holder and its watch mechanism projects into the air and the rotation is continued for drying the mechanism.

If it is desired to clean the watch mechanism in parts, the individual parts thereof may be placed into the cage 22 and the latter fastened to the disc 9 by means of the operating racks 14 in the manner previously described, and the

cleaning operation may be proceeded with in the same manner. The cage in rotating will cause the slanting partition 23 to act on the fluid for drawing it in through the ends of the cage and for expelling it out through the peripheral wall 5 of the cage.

The disc 9 is provided with slots 9' which aid in circulating the fluid through the clock mechanism. When a watch is clamped between the jaws 13, as shown in Fig. 4, the slots 9' extend beyond the inner edges of the jaws. The slots therefore permit fluid to flow from the back of the disc 9 into the space within the clamping jaws 13 for promoting circulation of the fluid through the watch mechanism when the disc is 15 rotated in the fluid medium.

We claim:

1. In a device of the character described, a base having two pairs of spring elements rising therefrom, a container adapted to be clamped between the spring elements, a cover for the container having tongues projecting therefrom, and spring members connecting the elements of each pair and being shaped to allow the cover to be placed on the container from above with the tongues projecting into the space between the spring members, the latter having downward curves adapted for engagement with the tongues when the cover is turned for clamping the cover upon the container.

2. In a device of the character described, a holder comprising a rotatably mounted disc, means on said disc for clamping an object to the surface thereof, and means for rotating the disc in a fluid medium for cleaning the object, the disc having slots extending from the center toward the rim to form a communication between the back of the disc and the space within the clamping means for promoting circulation when the object is rotated in the fluid medium.

3. In a device of the character described, a holder comprising a body having coacting jaws movable thereon for gripping an object, spring means urging the jaws upon the object and geared means for separating the jaws with means for locking the jaws in adjusted position.

4. In a device of the character described, a holder comprising a disc having coacting jaws movable thereon for gripping an object, racks connected with the jaws, a pinion engaging the racks for operating the jaws when the pinion is rotated, a shaft projecting from the pinion and extending through the disc, a sleeve threaded on the shaft and having a part axially spaced therefrom so as to form a chamber therewith, means for limiting the threaded movement of the sleeve away from the disc for causing the shaft to turn with the sleeve when rotary movement of the latter is continued whereby the turning of the shaft will turn the pinion and move the racks for separating the jaws, and a spring within the chamber opposing outward movement of the jaws and tending to urge the jaws upon an object inserted therebetween, the sleeve being adapted to urge the pinion upon the disc when the sleeve is threaded against the disc, the sleeve when contacting the disc and rotated further, moving the shaft for forcing the pinion against the disc for locking the pinion and jaws in adjusted position.

5. A container for a quantity of cleaning fluid, a cage for an object to be cleaned, said cage being of a diametral size a little more than one-half that of the container, means to suspend the cage eccentrically in and below the fluid in the

5 container so that the periphery of the cage extends past the vertical axis of the container, and means to rotate the first means and cage at a cleaning speed, the size of the cage and its eccentric position keeping the vortex forming in said fluid substantially coincident with the axis of the container.

10 6. A container for a quantity of cleaning fluid, supporting means to carry an object which is to be cleaned, said supporting means being of a diametral size a little more than one-half the diameter of the container, suspending means to suspend the supporting means eccentrically in and below the fluid in the container so that the 15 periphery of the supporting means extends past the vertical axis of the container, and means to rotate the suspending and supporting means at a cleaning speed, the size of the supporting means and its eccentric position keeping the vortex forming in said fluid substantially coincident with the axis of the container.

20 7. The herein described method of cleaning objects which consists in rotating them about an axis and in a rotating body of cleaning fluid, the axis extending into the fluid and being disposed laterally of the vortex formed by the rotating fluid, whereby the objects will be confined to the fluid and substantially clear of the foregoing vortex.

25 8. In a cleaning device of the character described, a holder having two gripping members for gripping an object, each gripping member having a face for the object to rest an and having a pair of slanting side members for urging the 30 object upon the faces of the gripping members and the side members of each pair being arranged at an angle to one another so as to cause the two pairs to coact in centering the object.

35 9. In a cleaning device of the character described, a vertically disposed perforated cylindri-

cal container for containing objects to be cleaned and having top and bottom end sections respectively, a perforated partition set at a slanting angle from the diametrical center line of the top end section toward the side and bottom end section, and means for rotating the container in a cleaning fluid, the slanting partition causing the fluid to be drawn in at the end sections and to be discharged at the peripheral side thereby creating circulation throughout the container. 10

10 10. In a cleaning device of the character described, a perforated container having a vertically disposed perforated partition slantingly disposed therein from the top to the bottom ends to form two compartments and means for rotating the 15 container in a cleaning fluid, the partition serving to cause the cleaning fluid to be drawn into the respective compartments from opposite ends and to be expelled laterally.

15 11. In a device of the character described, a 20 holder comprising a body having coacting jaws movable thereon for gripping an object, each jaw having inclined sides extending at an angle with respect to each other, and having their inner ends spaced from each other for providing a 25 stem receiving recess, and means for causing the jaws to grip a watch mechanism.

12. In a device of the type described, a rotatable cage for receiving watch parts, the cage having a cylindrical wall with a closed bottom and an open 30 top, a partition mounted in the cage and extending from the diametrical center of the open top toward the cage bottom, said partition being inclined with respect to the cage bottom for providing a large and a small compartment each 35 having the same size entrance opening, and a cover for the open top of the cage.
